(57) **CLAIM**

I claim the ornamental design for a semi-portable vehicle storage device, as shown and described.

DESCRIPTION

FIG. 1 is a right side view of the semi-portable vehicle storage device showing my novel design;

FIG. 2 is a left side view thereof;

FIG. 3 is a rear elevation view thereof;

FIG. 4 is a front elevation view thereof;

FIG. 5 is a top plan view thereof;

FIG. 6 is a bottom plan view thereof;

FIG. 7 is a perspective view thereof; and,

FIG. 8 is a perspective view thereof with the entry door partially retracted.

The broken line showing in FIG. 6 shows a typical texture of the interior and forms no part of the claimed design.
